UNITED STATES PATENT OFFICE.

FRANK LOTTER, OF ELKTON, MICHIGAN.

FORK.

No. 843,472.

Specification of Letters Patent.

Patented Feb. 5, 1907.

Application filed September 12, 1906. Serial No. 334,309.

To all whom it may concern:

Be it known that I, FRANK LOTTER, residing at Elkton, in the county of Huron and State of Michigan, have invented certain new and useful Improvements in Forks, of which the following is a specification.

My invention relates to certain new and useful improvements in forks, particularly adapted for use in lifting beans after they have been pulled with the ordinary bean-harvesters and for gathering and lifting from the ground sugar-beets, chickery-roots, and the like.

Primarily my invention has for its object to provide a fork of this character of a very simple and effective construction, that can be easily and cheaply manufactured, and which will readily and effectively serve its intended purposes.

Generically the invention comprises a fork similar to an ordinary pitchfork arranged with the prongs diverging from the body or back of the fork, and each prong is curved in side elevation into a shape approximately to that of a scythe-blade. Each tooth or prong also has its upper face concaved transversely throughout about three-fifths of its length from the back of the fork, and throughout the remaining two-fifths of its length each prong has its upper surface flat, so that the prongs of the fork will have a pair of knife or shearing edges at their upper faces throughout three-fifths of their length, while the prongs are otherwise substantially U-shaped in cross-section.

With other objects in view my invention also comprises a certain novel construction of fork, such as will be first described in detail and then be specifically pointed out in the appended claims, reference being had to the accompanying drawings, in which—

Figure 1 is a perspective view of my invention. Fig. 2 is a top plan view thereof. Fig. 3 is a side elevation thereof. Fig. 4 is a cross-section on the line 4-4 of Fig. 3. Fig. 5 is a similar view on the line 5-5 of Fig. 3.

Referring now to the accompanying drawings, in which like numerals and letters of reference indicate like parts in all of the figures, 50 1 designates the fork, which comprises a back 1^a and the handle-receiving socket 1^b, in which the handle 2 may be secured. The fork 1 also includes a plurality of prongs 1^c, arranged closer together at the back 1^a, with 55 which they may be integrally formed, and

projecting from the back 1^a in diverging directions, so that the points 1^d of the fork-prongs will be at a greater distance apart than where the prongs join with the back 1^a.

Each prong 1^c is curved in side elevation, 60 as shown in Fig. 2, and has its upper face 1^e concaved in cross-section, as at 1^f, for three-fifths of the length of the prong, beginning at the point where the prong joins the back 1^a and extending toward the point 1^d, but terminating about two-fifths the length of the prongs from the point 1^d. The remaining portion 1^g of the upper surfaces of the prong is flat across the top, as indicated. By reason of the concaved portion of the prong a 70 pair of knife-edges 1^h is produced on each prong, so that when the fork is placed under the beans, beets, or other like material the prongs will take a firm grip thereon.

In gathering beets or other roots the fork 75 is operated by passing over the root and under the stalks and leaves and pressing them into the narrow space between the prongs. The sharp edges of the prongs take a tight grip thereon, and the root is easily lifted 80 from the ground and thrown into heaps, as desired, after being first lifted and loosened with the common lifting-plow.

When my invention is used for gathering roots and the like, the shearing edges 1^h of 85 the prongs may be used to cut the roots as they are gathered up, and this action takes place owing to the fact that the prongs converge from the points to the back, and as the fork is shoved under the root the root is 90 wedged in between the prongs and at the same time cut by the knife or shearing edges 1^h.

From the foregoing description, taken in connection with the accompanying drawings, 95 it is thought the complete construction, operation, and many advantages of my invention will be readily understood by those skilled in the art to which it appertains.

What I claim is—

1. A fork, comprising a back, a handle-receiving portion projecting therefrom, a plurality of prongs diverging from the back, said prongs having their upper surfaces concaved throughout a portion of their length to provide knife-edges, substantially as shown and described.

2. A fork, comprising a back, a handle-receiving portion projecting therefrom, a plurality of prongs diverging from the back,

110

said prongs having their upper surfaces concaved throughout the major portion of their length.

3. A fork, comprising a back, a handle portion, and a plurality of prongs projecting from the back, said prongs having their upper surfaces concaved in cross-section from the back toward the points and having the portion of the upper surface of the prongs adjacent the points flat, substantially as shown and described.

4. A fork, comprising a back, a handle por-

tion, and a plurality of prongs projecting from the back, said prongs having their upper surfaces concaved in cross-section from the back toward the points and having the portion of the upper surface of the prongs adjacent the points flat, said prongs being curved in side elevation and diverging from the back to the points. 15

FRANK LOTTER.
